UNITED STATES PATENT OFFICE.

LEWIS C. HALL, OF WHEATLAND, WYOMING.

BEET AND COTTON THINNER.

Application filed January 29, 1927. Serial No. 164,566.

This invention relates to cotton and beet thinners and spacers.

One important object of this invention is to improve the general construction of devices of this character so that hand work in the thinning of cotton, beets, and other plants of similar habits may be eliminated.

A second important object of this invention is to provide a novel form of frame structure for such device wherein the chopping wheel common to these devices is carried on a supplemental frame adjustable in an improved manner on the main frame.

A third important object of this invention is to provide a novel arrangement of parts by means of which the shaft carrying the chopping wheel may be engaged and disengaged at will from the operating means and may also have its rear end lifted upwardly, when desired, so that the chopping wheel clears the growing plants.

A fourth important object of this invention is to provide a novel arrangement by which the front end of the chopping wheel shaft may be lifted bodily with the frame structure and the rear end lifted with respect to the frame structure.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of the invention.

Figure 2 is a side elevation thereof.

Figure 3 is a longitudinal section through the body of the invention.

Figure 4 is a front view of the chopper wheel.

Figure 5 is an elevation of a bracket for holding the blades on the wheel.

Figure 6 is a section on the line 6-6 of Figure 3.

Figure 7 is a section on the line 7-7 of Figure 3.

Figure 8 is an end view of one of the blades.

In the embodiment of the invention here shown there is provided a main frame having side members 10 and a rear member 11 which holds the rear ends of the side members apart. At the front end the side mem-

bers are bent inwardly toward each other as shown at 12 and are then bent forwardly as at 13 to support the usual tongue and draft gear 14. Through the side members 10 adjacent the rear end there extends a main shaft or axle 15 which projects well beyond the side frame members on each side. Splined on these projecting ends are the hubs 16 of rear wheels 17, these hubs being held in adjusted position by set screws 18. Preferably the axle, between the side frames 10 is covered with a housing 19 and on this axle is fixed a driving gear 20, the housing being suitably cut away to expose the forward portion of this driving gear. The forward end of the side frame members are provided with suitable boxes 21 through which slide the standards 22 carrying the front wheels 23. The upper ends of these standards are provided with grooves 24 and collars 25 are mounted on these standards and have set screws 26 projecting into the grooves. On each side frame member is pivoted a bell crank lever 27 the forward end of which is connected by a pin and slot connection with a respective collar 25. The rear end of each lever 27 is connected by a reach rod 28 with a latch lever 29 working over a quadrant 30 fixed on the rear frame member 11. Thus by operating the levers 29 the front of the main frame may be raised or lowered as desired.

Each of the side members 10 is provided, adjacent its forward end with a series of vertically spaced bolt openings 31 and spaced rearwardly from the openings 31 are similar openings 32. Between the side members 20 is located an inner secondary frame having side members 33, a front member 34 and a rear member 35. These side members 33 are adjustably connected to the side members 10 by means of bolts 36 at the front and rear, said bolts passing through the sides 33 and through selected openings 31 and 32 respectively. By this means the secondary frame may be raised or lowered bodily with respect to the main frame and there held. Also, the secondary frame may be tilted at either end to angular position with respect to the main frame and there held.

The frame member 34 is provided with a central opening 37 slightly greater in vertical dimension than in width and through this central opening extends the forward end of a shaft 38. The rear end of this shaft extends through a vertically elongated loop

or guide 39 and can thus be raised or lowered at the rear end with respect to the main frame. A pinion 40 is fixed on the rear end of the shaft 38 and normally meshes with 5 the gear 20. On the forward portion of the shaft 38 is fixed a collar 41 and between this collar and the front frame member 34 is a spring 42 which urges the shaft rearwardly and normally holds the pinion 40 10 in mesh with the gear 20. Fixed on the rear portion of the shaft 38 is a collar 43 and extending rearwardly from this collar is a reach rod 44 which has its rear end connected to a latch lever 45 working over a 15 quadrant 46 fixed to the member 11. By this means movement of the lever 45 forwardly will push the shaft 38 bodily against the action of the spring 42 and disengage the pinion 40 from the driving gear 20 so 20 that the operator of the machine can stop the shaft 38 when desired.

On this shaft 38 is fixed a chopper or thinner wheel 47 carrying on its periphery brackets 48 to which are adjustably connected 25 chopper blades 49. Thus, when the pinion and gear mesh the wheel 47 will rotate and the chopping or thinning operation may be carried out but by proper movement of the lever 45 the wheel 47 may be stopped from 30 rotation.

There is also connected to the collar 43 the front end of a pedal lever 50 which passes through and is slideable in a fulcrum 51 fixed on the housing 19. The rear end 35 of this lever is provided with a pedal 52 which is convenient to the operator's seat 53 carried by the member 11. Also the levers 29 and 45 will be convenient to this seat. By depressing the pedal 52 the collar 43 and 40 rear end of the shaft 38 may be raised in the loop 39, so that while the machine is being driven at times when it is desired that the chopper wheel and blades be not drawn through the growing plants, the wheel and 45 its plants may be lifted clear, this operation being, if necessary, assisted by raising the front end of the main frame by the levers 29. Preferably a rein guide 54 is carried on the main frame and arches over the wheel 50 47 to keep the reins from being entangled in the blades 46.

By reference to Figures 4 and 5 it will be seen that the wheel 47 is provided on each side with a groove 55 for the reception of 55 the ends of the securing bolts 56 so that the clips 48 may be adjusted. Also the rim of the wheel is divided by scale markings 57 so that the adjustment and even spacing of the blades 49 may be obtained. It is to 60 be understood that these blades are curved for proper chopping effect.

There has thus been provided a simple and

efficient device of the kind described and for the purpose specified.

It is obvious that minor changes may be 65 made in the form and construction of the invention without departing from the material spirit thereof. It is not, therefore, desired to confine the invention to the exact form herein shown and described, but it is 70 desired to include all such as properly come within the scope claimed.

Having thus described the invention, what is claimed as new, is:

1. In a beet thinner, a frame structure, 75 front and rear wheels supporting said frame structure, a thinner wheel shaft extending longitudinally of and supported by said frame structure, said shaft having its rear end supported for vertical movement with 80 respect to the frame structure, a thinner wheel carried by said shaft, a driving gear actuated from said rear wheels, a driven pinion on the rear end of said shaft and connected to the shaft for driving the same, 85 said pinion being normally in mesh with the driving gear, said shaft being slideable longitudinally in said frame structure, a spring urging said shaft rearwardly and the pinion into engagement with said gear, 90 a collar fixed on said shaft, a latch lever and quadrant mounted on the frame structure, a reach rod connecting the collar and the latch lever to move the shaft longitudinally as the lever is moved, and means to lift the 95 rear end of the shaft with respect to the frame structure.

2. In a beet thinner, a frame structure, 100 front and rear wheels supporting said frame structure, a thinner wheel shaft extending longitudinally of and supported by said frame structure, said shaft having its rear end supported for vertical movement with 105 respect to the frame structure, a thinner wheel carried by said shaft, a driving gear actuated from said rear wheels, a driven pinion on the rear end of said shaft and connected to the shaft for driving the same, 110 said pinion being normally in mesh with the driving gear, said shaft being slideable longitudinally in said frame structure, a spring urging said shaft rearwardly and the pinion into engagement with said gear, a collar fixed on said shaft, a latch lever and quadrant mounted on the frame structure, a reach rod connecting the collar and the latch lever to move the shaft longitudinally as the lever is moved, a pedal lever having one end connected to said collar, and a fixed 115 fulcrum through which the pedal lever slides and in which said pedal lever is vertically tiltable to raise the rear end of said shaft.

In testimony whereof I affix my signature.

LEWIS C. HALL.
